US00D824525S

(12) **United States Design Patent** (10) **Patent No.:** **US D824,525 S**
Lacy et al. (45) **Date of Patent:** **** *Jul. 31, 2018**

(54) RELEASE PAPER FOR WOUND TREATMENT DEVICES	4,080,348 A	3/1978	Korpman
	4,126,130 A *	11/1978	Cowden A61F 13/0203 602/22
(71) Applicant: Ethicon, Inc. , Somerville, NJ (US)	4,140,115 A	2/1979	Schonfeld
(72) Inventors: Shane A. Lacy , Bound Brook, NJ (US); Julian A. Quintero , Flemington, NJ (US); Chin Park , Jersey City, NJ (US); Frank S. Leparik , Greenlawn, NY (US)	4,263,906 A	4/1981	Finley
(73) Assignee: Ethicon LLC , San Lorenzo, PR (US)	4,313,865 A	2/1982	Teramoto et al.
(*) Notice: This patent is subject to a terminal disclaimer.	4,340,043 A	7/1982	Seymour
(**) Term: 14 Years	4,364,876 A	12/1982	Kimura et al.
(21) Appl. No.: 29/503,320	4,390,519 A *	6/1983	Sawyer A61L 15/325 128/DIG. 8
(22) Filed: Sep. 25, 2014	4,460,369 A	7/1984	Seymour

CLAIM

We claim the ornamental design for a release paper for wound treatment devices, as shown and described.

DESCRIPTION

FIG. 1 is an underside plan view of an ornamental release paper for wound treatment devices in accordance with the present invention showing our new design;

FIG. 2 is a top plan view thereof;

FIG. 3 is a front elevation thereof;

FIG. 4 is a rear elevation thereof;

FIG. 5 is a left side elevation thereof;

FIG. 6 is a right side elevation thereof;

FIG. 7 is an underside plan view of an ornamental release paper for wound treatment devices in accordance with a second embodiment of the present invention showing our new design;

FIG. 8 is a top plan view thereof;

FIG. 9 is a front elevation thereof;

FIG. 10 is a rear elevation thereof;

FIG. 11 is a left side elevation thereof;

FIG. 12 is a right side elevation thereof;

FIG. 13 is an underside plan view of an ornamental release paper for wound treatment devices in accordance with a third embodiment of the present invention showing our new design;

FIG. 14 is a top plan view thereof;

FIG. 15 is a front elevation thereof;

FIG. 16 is a rear elevation thereof;

FIG. 17 is a left side elevation thereof;

FIG. 18 is a right side elevation thereof;

FIG. 19 is an underside plan view of an ornamental release paper for wound treatment devices in accordance with a fourth embodiment of the present invention showing our new design;

FIG. 20 is a top plan view thereof;

FIG. 21 is a front elevation thereof;

FIG. 22 is a rear elevation thereof;

FIG. 23 is a left side elevation thereof;

FIG. 24 is a right side elevation thereof;

FIG. 25 is an underside plan view of an ornamental release paper for wound treatment devices in accordance with a fifth embodiment of the present invention showing our new design;

FIG. 26 is a top plan view thereof;

FIG. 27 is a front elevation thereof;

FIG. 28 is a rear elevation thereof;

FIG. 29 is a left side elevation thereof; and,

FIG. 30 is a right side elevation thereof.

The broken lines showing the environment in the drawings is for illustrative purposes only and forms no part of the claimed design.
